UNITED STATES PATENT OFFICE.

JOHN R. FLOOD, OF SPOKANE, WASHINGTON, ASSIGNOR TO UNIQUE SPECIALTY COMPANY, OF SPOKANE, WASHINGTON, A CORPORATION.

VAULT-DOOR.

1,071,723.

Specification of Letters Patent.

Patented Sept. 2, 1913.

Application filed March 3, 1913. Serial No. 751,750.

To all whom it may concern:

Be it known that I, JOHN R. FLOOD, a citizen of the United States of America, residing at Spokane, in the county of Spokane and State of Washington, have invented certain new and useful Improvements in Vault-Doors, of which the following is a specification.

This invention relates to vault closures and more particularly to mechanism for operating the same conveniently, especially cement doors or other doors comprising heavy or bulky substance.

A particular object of the invention is to provide a substantial mechanism whereby the doors may be raised and lowered without having to manually lift the weight of the same and without danger of them falling and injuring the operator or others.

Other objects and purposes will be disclosed by the mechanism shown in the accompanying drawings, shown in a single figure.

Two doors are shown adapted for covering a single opening. The door 10 is shown in a closed position and the door 11 in an open position. The particular application of the device as shown in the drawings is to a pair of doors in a pavement leading to a basement. At the edges of the opening 13, perpendicularly arranged are rails 14 reaching from a point near the top of the opening to the floor of the basement or to some substantial support. Suspended from the pavement 15 are pulleys 16. Engaging the rails 14 as guides are shoes 17, to which shoes are pivotally attached rods 18, as at 19. Weights 20 serving as counter balances to the doors 10 and 11 are attached to cables 21, such cables passed over the pulleys 16 and attached to the shoes 17, leaving the weights 20 suspended. The rods 18 being pivotally connected at one end to the doors 10 and 11 as at 22. The rods 18 instead of being straight are slightly deflected as at 23, thereby giving the upper portions thereof a curve inwardly, the purpose being to have the rods 18 of such construction that when the doors are thrown open, the same will be permitted to swing upwardly a little beyond the perpendicular, so that gravity will maintain them in an open position without other assistance, as shown by the open position of

the door 11. Each door has an independent mechanism and may be operated separately. 55

The doors 10 and 11 being counter-balanced by the weights 20 are easily lifted from either a position below the doors or above the same, and are closed by a light push against them without any danger of 60 them slamming or being drawn down at a dangerous speed. In the practical operation of the parts in opening and closing a door, the doors are lifted by the operator with the assistance of the counter balance, 65 the shoes 17 pass upwardly along the rails 14 as supports, the cables 21 are carried over the pulleys 16 and the weights 20 are carried downward leaving the mechanism as shown in the drawings as applied to the 70 open door 11. In closing the doors the operation is reversed, leaving the mechanism as shown in the drawings as applied to the closed door 10.

What I claim is,

1. In vault doors, a door hinged at a permanent position, guide posts extending downwardly from a position near the hinges, pulleys suspended from a permanent position in the vicinity of the guide posts, shoes 80 adapted to follow the guide posts, rods reaching from the tiltable end of the door and pivoted thereto reaching to and pivoted to the shoes and counter-balances attached to cables and suspended over the pulleys, the 85 opposite ends of the cables being attached to the shoes.

2. In vault doors, a door hinged at a permanent position, guide posts extending downwardly from a position near the hinges, 90 pulleys suspended from a permanent position in the vicinity of the guide posts, shoes adapted to follow the guide posts, rods pivoted to the tiltable end of the door and reaching downwardly to and pivoted to the 95 shoes and bent to deflect their upper ends inwardly, together with counterbalances attached to cables and suspended over the pulleys, the opposite ends of the cables being attached to the shoes.

3. In vault doors, a door hinged at a permanent position, guide posts extending downwardly from a position near the hinges, 100 shoes adapted to follow the guide posts, rods pivoted to the tiltable end of the door and reaching to and pivoted to the shoes and 105

bent to deflect their upper ends inwardly, together with a counterbalance attached to said shoes.

4. In vault doors, a door hinged at a permanent position, guide posts extending downwardly from a position near the hinges, shoes adapted to follow the guide posts, rods pivoted to the tiltable end of the door and reaching to and pivoted to the shoes and

bent to deflect their upper ends inwardly together with means for raising and lowering said shoes along the guide posts. 10

In testimony whereof I affix my signature in presence of two witnesses.

JOHN R. FLOOD.
